UNITED STATES PATENT OFFICE.

CHARLES E. GIERDING, OF NEWARK, NEW JERSEY.

FARE-REGISTER.

No. 833,041.

Specification of Letters Patent.

Patented Oct. 9, 1906.

Application filed August 3, 1905. Serial No. 272,596.

To all whom it may concern:

Be it known that I, CHARLES E. GIERDING, a citizen of the United States of America, and a resident of Newark, in the State of New Jersey, have invented a new and useful Improvement in Fare-Registers, of which the following is a specification.

This invention relates to those fare-registers in which provision is made for making a printed record at the end of each trip to facilitate obtaining with certainty the details of the individual trips for purposes of comparison and as an additional safeguard against the failure of conductors to properly 15 register the fares and to "set" the register at the end of each trip.

The present invention consists in certain novel combinations of parts hereinafter described and claimed.

20 The leading object of the invention is to provide for setting the customary trip-register, together with the direction-indicator, hereinafter termed the "trip-indicator," if there be one, at the end of each trip, and for 25 unlocking and relocking the registering mechanism at the beginning and end of each setting operation, and by the same means to provide for setting or adjusting a trip-indication printing device and for printing the 30 indications of the preceding trip, including the number indicated by one of the registers or a sufficient portion of such number-indication without adding to the labor or responsibility of the conductor.

35 Other objects are to adjust a set of type-wheels simultaneously with the registration of the fares by a shaft and spur-gearing connection between the units-wheel of the permanent register and the units-type wheel, to 40 provide for adjusting the trip-indication printing device simultaneously with the setting of the trip-indicator by a simple lost-motion connection between the two, to provide for the printing movement by a cam 45 carried by the main setting-shaft, to adapt the same shaft to support a rotary platen or record-strip drum, to actuate this drum by motion transmitted from said main setting-shaft through Geneva stop-wheels and spur-gearing, and to operate the trip-indicator 50 and trip-indication printing device in such a way as to hold them steadily in their respective positions of rest.

Three sheets of drawings accompany this 55 specification as part thereof.

Figures 1 and 2 are respectively side and

front views of the improved register including its hanging back. Fig. 3 is a fragmentary side view, on a larger scale, of the register proper with the printing-device door 6c open. Fig. 4 is a face view on the same scale as Fig. 3 with the front part of the register-casing and dial-plate omitted and the record-strip drum in section, showing a cross-section of the record-strip. Fig. 5 represents a 65 face view of the record-strip removed and flattened. Fig. 6 is a sectional side view of the register, or so much thereof as is shown in Fig. 4, minus the record-strip drum, with the printing device in the foreground. Fig. 7 70 is a like view from the same side with some additional parts, including the type-wheels and their frame, omitted so as to expose to view parts behind, and with the trip-indicator and trip-indication printing device in 75 their opposite positions of rest, one of the omitted parts being represented in dotted outline; and Fig. 8 is a view of the record-strip drum detached, showing its inner end.

Like reference characters refer to like 80 parts in all the figures.

The specific fare-register represented by the drawings includes a "hanging back" A, Figs. 1 and 2, supporting primary actuating mechanism (represented by levers 1 and 2 in 85 Figs. 1 and 2) and the register proper, (shown at B in Figs. 1 and 2,) detachably fastened to said hanging back and containing secondary actuating mechanism, represented by its re-tracting-spring, spring-lever, and main slide 90 at 3, 4, and 5, respectively, in Figs. 6 and 7.

The register proper, to which Figs. 3, 4, 6, 7, and 8 are confined, further contains a "trip-register," preferably and conveniently of the numeral-wheel type, (represented at a,) 95 a "permanent register" of that type, (represented at b,) and a set of type-wheels c, all three having horizontal axes and all of them simultaneously actuated step by step by said actuating mechanism in the registering operation. A suitable bell mechanism, the bell of which is shown at d in Fig. 4, is actuated during the registration of each fare or unit, as is customary, by the same actuating mechanism. As the details of said actuating mechanism and said bell mechanism form no part of the present invention, further description thereof in the present specification is deemed unnecessary and is omitted.

The improved register also preferably and 110 conveniently contains an actuation-indicator e, movable with the trip-register wheels and

exposed to view during each registering operation so as to indicate the fact if this operation is not completed; also a trip-indicator *f*, movable on a horizontal axis to expose the indications "In" and "Out" or like alternating indications at the ends of the respective trips. Such indications, and those of the trip-register *a* and permanent register *b*, respectively, are exposed to view through horizontal sight-openings 6, 7, and 8 in the dial-plate *g*, Fig. 2, behind the glass front plate *h*, which, together with two circular main parts *i* and *j* of the casing and a side door *k*, inclose all the parts herein referred to as within the register proper. Said main parts *i* and *j* are respectively, by preference, a suitable hollow casting *i*, forming a back plate and one-half, more or less, of the circumferential wall of the casing, and a front part *j*, of sheet metal, interlocked with said back part by bayonet-joints, (represented by their pins 9 in Fig. 4.) The dial-plate *g* and glass front plate *h* are supported at a proper distance in front of the internal mechanism by posts 10 (shown in end view by Fig. 4) and by the customary overhanging flange 11 at the front of said sheet-metal front part *j*.

The door *k* is hinged to the back part *i* and is fastened in its closed position by means 30 of a lock 12, the bolt of which interlocks with the front part of the casing. This door is unlocked and opened, and a setting knob or key *l* is unscrewed and detached in order to separate the parts of the casing. The key *l* is shown attached in Fig. 4 by way of accommodation. The setting mechanism actuated by said key *l* is characterized by a horizontal shaft 13, which is the shaft of the trip-register *a* and is normally stationary, being rotated in 40 the setting operation by turning said key *l* to bring the zero-mark (0) of each of the trip-register numeral-wheels behind their window 7 in the dial-plate *g*, Fig. 2, at the end of each trip. This shaft is also preferably and conveniently extended longitudinally so as to support the bell *d* at its right-hand end and at its left-hand end to support a rotary platen or record-strip drum *m* in juxtaposition to said type-wheels *c*. 45 The shaft 14 of the permanent register *b* is fast within its units-wheel and is extended longitudinally so as to protrude at the left-hand side of the pair of frame-plates *n* and *o*, between which the trip-register and permanent register-wheels rotate. At its protruding end said shaft 14 carries a spur-wheel 15, that is normally in mesh with a like spur-wheel 16, formed on or fixedly attached to the units-wheel of said set of type-wheels *c*, 55 which are thus made to rotate synchronously with the corresponding wheels of the permanent register *b* in the registering operation. The shaft 17 of said type-wheels *c* is loose with reference to all of them and is provided 60 on its inner end with a two-armed lever or

cam 18, and at or near its outer end with a trip-indication printing device *p* in the form of a type-block, which may carry (in reverse) one or both of the indications of the trip-indicator *f*. Preferably it carries one of said indications—"In," for example—and parallel therewith the serial number of the individual register 168, so as to print this number instead of the alternating trip-indication "Out" and thus to obviate printing both in order to identify the record with the individual register making the same. Said shaft 17 of the type-wheels *c* and a parallel shaft 19, supporting the pinions 20 and 21 of spur-gearing-carrying mechanism, are mounted in a vertically-slidable frame *q*, that is attached to the left-hand frame-piece *n* by guide-screws 22 and 23, extending through longitudinal slots in the slidable frame. This type-wheel frame *q* is normally held in its lowermost position by gravity and by the tension of a retracting-spring *r*. It is moved upwardly in the printing operation by a cam 24, carried by said horizontal setting-shaft 13 and embraced by a yoke 25 at the upper end of the type-wheel frame *q*. This yoke 25 is conveniently made integral with the body of the frame, as shown, and at the same time adjustable to regulate the impression on the record-slip *s* by suitably shaping the frame *q* and providing the same with a horizontal slit 26, crossed by an adjusting-screw 27. (See Fig. 6.) The type-wheel shaft 17 is turned on its axis to adjust said type-block *p* for the printing operation in the act of setting the trip-register *a* and trip-indicator *f* for the next trip by the following means: The left-hand extension of said horizontal setting-shaft 13 carries a pinion or small spur-wheel 28, in mesh with a spur-wheel 29 of twice its diameter, and the latter is provided with a crank-pin 30, that projects, together with the head of a stud-screw 31, forming the shaft of said spur-wheel, through a suitably-shaped oval opening 32 in a lever *t*, that is movable on a horizontal pivot 33 near the back of the register and at its front end is coupled by a pin-and-slot connection 34 with a connecting-bar *u*, the upper end of which is coupled to a crank-arm 35, fast on the rock-shaft 36, that carries the trip-indicator *f*, while the lower end of the connecting-bar carries a stud-pin 37 to interact with said two-armed cam 18 on the type-wheel shaft 17. The play of this end of said connecting-bar *u* is suitably limited by a screw 38, attaching it to the adjacent frame-plate *n* and embraced by a longitudinal slot in the bar. The construction and arrangement of these parts is such that when the trip-indicator *f* is moved to expose its indication "In," the type-block *p* is moved so as to bring its corresponding type-face "In" into line with the printing type-faces of the type-wheels *c*, and when the trip-indicator *f* is moved so as to 130

expose its indication "Out," said type-block *p* is moved so as to bring the register-number 168 into line with said printing type-faces of the type-wheels. The trip-indication type-block *p* is thus adjusted at the end of each printing operation preparatory to the next printing operation. Said spur-wheel 29 further carries on its outer face the driving member of Geneva stop-gearing 39 39', by 5 which rotary motion is transmitted intermittently to a pinion 40, in mesh with a spur-wheel 41, carried by the record-strip drum *m*, within the latter and concentric with the setting-shaft 13. By this means the record-strip *s* is advanced one space after each printing operation in the act of setting the trip-register *a* and trip-indicator *f* and without at 10 all complicating the mechanism.

The record-trip drum *m* is held in place on 20 the setting-shaft 13 by a rigid inwardly-projecting finger 42 on the door *k*, which door is normally shut and is secured in its closed position by its said lock 12. When opened, the door exposes the record-strip drum, as in Fig. 25 3, so that it may be readily withdrawn by grasping its hub 43 from within the register. The record-strip *s* is preferably and conveniently made of the shape represented by Fig. 5, with its ends 44 reduced in width by notches 45, so as to provide for holding the strip in place around the drum by means of its ends 44, extending inwardly through a slit 46 in the periphery of the drum, without cutting such slit entirely through the periphery, and 35 thus making the drum liable to get out of shape. The unbroken side or inner end of the drum is shown in Fig. 8.

The type-wheels *c* may obviously be increased or reduced in number with reference 40 to the numeral-wheels of the permanent register *b*, the trip-indications printed by the type-block *p* may be identical with those of the trip-indicator *f*, if preferred, and other like modifications will suggest themselves to 45 those skilled in the art.

Having thus described said improvement, I claim as my invention and desire to patent under this specification—

1. The combination, in a fare-register, of 50 actuating mechanism, a trip-register, a permanent register and a set of type-wheels actuated in common, step by step, by said mechanism in the registering operation, means for setting said trip-register at the end of each trip, a movable frame in which said type-wheels are mounted, and motion-transmitting connections between said setting means and said frame, whereby the indications of one of said registers at the end of 55 each trip are printed in the act of setting the trip-register.

2. The combination, in a fare-register, of 60 actuating mechanism, a trip-register, a permanent register and a set of type-wheels ac-

tuated in common, step by step, by said mechanism in the registering operation, means for setting said trip-register at the end of each trip, a movable frame in which said type-wheels are mounted, and motion-transmitting connections between said setting means and said frame, whereby the indications of the permanent register at the end of each trip are printed in the act of setting the trip-register. 65

3. The combination, in a fare-register, of 70 actuating mechanism, a trip-register, a permanent register and a set of type-wheels actuated in common, step by step, by said mechanism in the registering operation, a trip-indication printing device, means for 75 setting said trip-register at the end of each trip, a movable frame in which said type-wheels and printing device are mounted, and motion-transmitting connections between said setting means and said frame, whereby the indications at the end of each trip are 80 printed and the trip-indication printing device is adjusted for the succeeding trip in the act of setting the trip-register. 85

4. The combination, in a fare-register, of 90 actuating mechanism, a trip-register, a permanent register and a set of type-wheels actuated in common, step by step, by said mechanism in the registering operation, a trip-indicator, a trip-indication printing device movable with said trip-indicator, means for setting said trip-register and said trip-indicator at the end of each trip, a movable frame in which said type-wheels and printing device are mounted, and motion-transmitting connections between said setting means and said frame, whereby the indications at the end of each trip are printed and the trip-indication printing device is adjusted for the succeeding trip in the act of setting the trip- 95 register and trip-indicator. 100

5. The combination with suitable actuating mechanism of a trip-register, a numeral-wheel permanent register and a set of type-wheels actuated in common step by step by 110 said mechanism in the registering operation, said permanent register having a longitudinally-extended shaft rotatable with its units-wheel, and spur-gearing connecting the extension of said shaft with the units-wheel of 115 said type-wheels.

6. The combination with suitable actuating mechanism of a trip-register, a numeral-wheel permanent register and a set of type-wheels actuated in common step by step by 120 said mechanism in the registering operation, said permanent register having a longitudinally-extended shaft rotatable with its units-wheel, and said type-wheel set having a shaft on which all its wheels are loose, spur-gearing connecting the extension of said permanent register-shaft with the units-type wheel, 125 a trip-indication printing device carried by

4

said type-wheel shaft and means for periodically adjusting said printing device through the medium of this shaft.

7. The combination with suitable actuating mechanism of a trip-register, a permanent register and a set of type-wheels actuated in common step by step by said mechanism in the registering operation, said type-wheel set having a shaft on which all its wheels are loose, a trip-indication printing device carried by this shaft, a trip-indicator movable by a rock-shaft parallel to said type-wheel shaft and means for simultaneously setting the trip-register, trip-indicator and trip-indication printing device at the end of each trip.

8. The combination with suitable actuating mechanism of a trip-register, a permanent register and a set of type-wheels actuated in common step by step by said mechanism in the registering operation, said type-wheel set having a shaft on which all its wheels are loose, a trip-indication printing device carried by this shaft, a trip-indicator movable by a rock-shaft parallel to said type-wheel shaft and means for simultaneously setting the trip-register, trip-indicator and trip-indication printing device at the end of each trip, said means including a rotatable setting-shaft, spur-gearing transmitting motion therefrom including a wheel making half a turn during each rotation of said setting-shaft, a lost-motion crank and lever device operated by said wheel, a connecting-bar coupled to this device and to a crank on said rock-shaft and provided at its other end with a stud-pin, and a two-winged cam on said type-wheel shaft engaged by said stud-pin, to turn said type-wheel shaft and thereby with said trip-indication printing device, and to hold the latter in its respective positions of rest.

9. The combination with suitable actuating mechanism of a trip-register, a numeral-wheel permanent register and a set of type-wheels actuated in common step by step by said mechanism in the registering operation, said permanent register having a longitudinally-extended shaft rotatable with its units-wheel, spur-gearing connecting the extension of said shaft with the units-wheel of said type-wheels, a movable frame in which said type-wheels are mounted, and means for moving said frame to print the record at the end of each trip.

10. The combination with suitable actuating mechanism of a trip-register, a numeral-wheel permanent register and a set of type-wheels actuated in common step by step by said mechanism in the registering operation, said permanent register having a longitudinally-extended shaft rotatable with its units-wheel, and said type-wheel set having a shaft on which all its wheels are loose, spur-gearing

connecting the extension of said permanent register shaft with the units type-wheel, a trip-indication printing device carried by said type-wheel shaft, means for periodically adjusting said printing device through the medium of this shaft, a movable frame in which said type-wheel shaft is mounted, and means for moving said frame to print the record at the end of each trip.

11. The combination with suitable actuating mechanism of a trip-register, a permanent register and a set of type-wheels, actuated in common step by step by said mechanism, a movable frame in which said type-wheels are mounted, and means for setting said trip-register and moving said frame to print the record at the end of each trip, such means including a setting-key, a setting-shaft rotated by said key, and a cam carried by said shaft and operating to move said frame when said shaft is turned.

12. The combination with suitable actuating mechanism of a trip-register, a permanent register and a set of type-wheels, actuated in common step by step by said mechanism, a vertically-movable frame in which said type-wheels are mounted, and means for setting said trip-register and moving said frame to print the record at the end of each trip, such means including a setting-key, a horizontal setting-shaft rotated by said key, and a cam carried by said shaft and operating to move said frame upward to its printing position when said shaft is turned.

13. The combination with suitable actuating mechanism of a trip-register, a permanent register and a set of type-wheels, actuated in common step by step by said mechanism, a spring-retracted movable frame in which said type-wheels are mounted, and means for setting said trip-register and moving said frame to print the record at the end of each trip, such means including a setting-key, a setting-shaft rotated by said key, and a cam carried by said shaft and operating to move said frame against the resistance of said spring when said shaft is turned.

14. The combination with suitable actuating mechanism of a trip-register, a permanent register and a set of type-wheels, actuated in common step by step by said mechanism, a vertically-movable frame in which said type-wheels are mounted, and which is provided with a cam-embracing yoke, and means for setting said trip-register and moving said frame to print the record at the end of each trip, such means including a setting-key, a horizontal setting-shaft rotated by said key, and a cam carried by said shaft within said yoke and operating to move said frame when said shaft is turned.

15. The combination with suitable actuating mechanism of a trip-register, a permanent register and a set of type-wheels, actu-

ated in common step by step by said mechanism, a spring-retracted movable frame in which said type-wheels are mounted and which is provided with a cam-embracing 5 yoke, and means for setting said trip-register and moving said frame to print the record at the end of each trip, such means including a setting-key, a setting-shaft rotated by said key, and a cam carried by said shaft within 10 said yoke and operating to move said frame, against the resistance of said spring, when said shaft is turned.

16. The combination with suitable actuating mechanism of a trip-register, a permanent register and a set of type-wheels, actuated in common step by step by said mechanism, a movable frame in which said type-wheels are mounted, and which is provided with an adjustable cam-embracing yoke, 15 means for setting said trip-register and moving said frame to print the record at the end of each trip, such means including a setting-key, a setting-shaft rotated by said key, and a cam carried by said shaft within said yoke 20 and operating to move said frame when said shaft is turned, and means for adjusting said yoke to regulate the printing-impression.

17. The combination with suitable actuating mechanism of a trip-register, a permanent register and a set of type-wheels, actuated in common step by step by said mechanism, a movable frame in which said type-wheels are mounted, and having a yoke integral therewith and a slit rendering said 30 yoke adjustable, means for setting said trip-register and moving said frame to print the record at the end of said trip, such means including a setting-key, a setting-shaft rotated by said key, and a cam carried by said 35 shaft within said yoke and operating to move said frame when said shaft is turned, and a yoke-adjusting screw crossing said slit for regulating the printing impression.

18. The combination with suitable actuating mechanism of a trip-register, a permanent register and a set of type-wheels, actuated in common step by step by said mechanism, a movable frame in which said type-wheels are mounted, a rotatable record-strip 45 drum in juxtaposition to said type-wheels, and means for setting said trip-register and moving said frame to print the record at the end of each trip, and for turning said drum after each printing-impression, such means including a setting-key, a setting-shaft rotated by said key, a cam carried by said shaft and operating to move said frame when said shaft is turned, and gearing transmitting motion from said shaft to said drum.

60 19. The combination with suitable actuating mechanism of a trip-register, a permanent register and a set of type-wheels, actuated in common step by step by said mechanism, a movable frame in which said type-wheels are mounted, a rotatable and with-

drawable record-strip drum in juxtaposition to said type-wheels, and means for setting said trip-register and moving said frame to print the record at the end of each trip, and for turning said drum after each printing-impression, 70 such means including a setting-key, a setting-shaft rotated by said key, a cam carried by said shaft and operating to move said frame when said shaft is turned, stop-gearing driven by said shaft and spur-gearing transmitting 75 motion from said stop-gearing to said drum.

20. The combination with suitable actuating mechanism of a trip-register, a permanent register and a set of type-wheels, actuated in common step by step by said mechanism, a 80 movable frame in which said type-wheels are mounted, a rotatable record-strip drum constructed with a peripheral slit in the direction of its axis extending only part way through from one end to receive and hold the 85 ends of the record-strip and mounted in juxtaposition to said type-wheels, and means for setting said trip-register and moving said frame to print the record at the end of each trip, and for turning said drum after each 90 printing-impression, such means including a setting-key, a setting-shaft rotated by said key, a cam carried by said shaft and operating to move said frame when said shaft is turned, and mechanism transmitting inter- 95 mittent rotation from said shaft to said drum.

21. The combination, in a fare-register, of actuating mechanism, a numeral-wheel trip-register, a permanent register and a set of type-wheels operated in common by said 100 mechanism, a rotatable record-strip drum in juxtaposition to the printing-faces of said type-wheels, means for setting said trip-register at the end of each trip including a setting-key and a setting-shaft rotatable there- 105 with, which is the shaft of said trip-register and which has a longitudinal extension upon which said record-drum is loosely mounted, means for taking the impression of said type-wheels at the end of each trip including a 110 movable frame in which said type-wheels are mounted and mechanism transmitting motion from said setting-shaft to said frame during the setting operation, and means for turning said drum after each impression in- 115 cluding mechanism transmitting intermittent rotation thereto from said setting-shaft.

22. The combination, in a fare-register, of actuating mechanism, a numeral-wheel trip-register, a permanent register and a set of type-wheels operated in common by said mechanism, said permanent register having a longitudinally-extended shaft rotatable with its units-wheel, gearing transmitting rotation from said shaft to said type-wheels, a rotatable record-strip drum in juxtaposition to the printing-faces of said type-wheels, means for setting said trip-register at the end of each trip including a setting-key and a setting-shaft rotatable therewith, 125 130

- which is the shaft of said trip-register and which has a longitudinal extension upon which said record-drum is loosely mounted, means for taking the impression of said type-wheels at the end of each trip including a movable frame in which said type-wheels are mounted and mechanism transmitting motion from said setting-shaft to said frame during the setting operation, and means for turning said drum after each impression including mechanism transmitting intermittent rotation thereto from said setting-shaft.
23. The combination, in a fare-register, of actuating mechanism, a numeral-wheel trip-register, a numeral-wheel permanent register, and a set of type-wheels operated in common by said mechanism, said permanent register having a longitudinally-extended shaft rotatable with its units-wheel, and said type-wheels having an oscillatable shaft on which all of them are loose, gearing transmitting rotation from said permanent-register shaft to said type-wheels, a trip-indication type-block carried by said type-wheel shaft, a rotatable record-strip drum in juxtaposition to the printing-faces of said type-wheels and type-block, means for setting said trip-register at the end of each trip, including a setting-key and a setting-shaft rotatable therewith which is the shaft of said trip-register and which has a longitudinal extension upon which said record-drum is loosely mounted, means for taking the impression of said type-wheels and type-block at the end of each trip including a movable frame in which said type-wheel shaft is mounted and mechanism transmitting motion from said setting-shaft to said frame during the setting operation, and means for setting said type-block and turning said drum after each impression including mechanism transmitting motion thereto from said setting-shaft.
24. The combination, in a fare-register, of actuating mechanism, a numeral-wheel trip-register, a numeral-wheel permanent register, and a set of type-wheels operated in common by said mechanism, said permanent register having a longitudinally-extended shaft rotatable with its units-wheel and said type-wheels having an oscillatable shaft on which all of them are loose, gearing transmitting rotation from said permanent-register shaft to said type-wheels, a trip-indicator, a trip-indication type-block carried by said type-wheel shaft, a rotatable record-strip drum in juxtaposition to the printing-faces of said type-wheels and type-block, means for setting said trip-register at the end of each trip, including a setting-key and a setting-shaft rotatable therewith which is the shaft of said trip-register and which has a longitudinal extension upon which said record-drum is loosely mounted, means for taking the impression of said type-wheels and type-block at the end of each trip including a movable

frame in which said type-wheel shaft is mounted and mechanism transmitting motion from said setting-shaft to said frame during the setting operation, and means for setting said trip-indicator and type-block and turning said drum after each impression including mechanism transmitting motion thereto from said setting-shaft.

25. The combination, in a fare-register, of actuating mechanism, a numeral-wheel trip-register, a numeral-wheel permanent register, and a set of type-wheels operated in common by said mechanism, all of them having horizontal axes, said permanent register having a longitudinally-extended shaft rotatable with its units-wheel, and said type-wheels having an oscillatable shaft on which all of them are loose, gearing transmitting rotation from said permanent-register shaft to said type-wheels, a trip-indicator having a horizontal rock-shaft, a trip-indication type-block carried by said type-wheel shaft, a rotatable record-strip drum in juxtaposition to the printing-faces of said type-wheels and type-block, means for setting said trip-register at the end of each trip, including a setting-key and a setting-shaft rotatable therewith which is the shaft of said trip-register and which has a longitudinal extension upon which said record-drum is loosely mounted, means for taking the impression of said type-wheels and type-block at the end of each trip including a movable frame in which said type-wheel shaft is mounted and mechanism transmitting motion from said setting-shaft to said frame during the setting operation, and means for setting said trip-indicator and type-block and turning said drum after each impression including mechanism transmitting motion thereto from said setting-shaft.

26. The combination, in a fare-register, of means for printing a record of the trips, including a record-strip support inclosed within the register-casing, register-casing parts one of which is rotatable relatively to the other to unlock and detach the rotatable part, and an outwardly-swinging door affording access to said record-strip support through an opening common to said casing parts, said door being hinged to one of said parts and fastened to the other part when closed, whereby the separation of said casing parts when said door is closed is prevented.

27. The combination, in a fare-register, of means for printing a record of the trips, including a record-strip support inclosed within the register-casing, front and rear register-casing parts one of which is rotatable relatively to the other to unlock and detach the rotatable part, and an outwardly-swinging side door affording access to said record-strip support through an opening common to said casing parts, said door being hinged to one of said parts and fastened to the other part when closed, whereby the separation of said

casing parts when said door is closed is prevented.

28. The combination, in a fare-register, of means for printing the indications at the end 5 of each trip including a record-strip drum, front and rear register-casing parts that are circular and separably connected with each other by bayonet-joint devices, and an outwardly-swinging side door affording access to said drum through an opening common to said casing parts, said door being hinged to one of said parts and 10 fastened to the other part when closed, and provided with a rigid finger arranged to contact with said drum when the door is closed, whereby the separation of said casing parts when said door is closed is 15 prevented.

29. The combination, in a fare-register, of means for printing the indications at the end

of each trip including a removable record-strip drum, front and rear register-casing parts that are circular and separably connected with each other by bayonet-joint devices, and an outwardly-swinging side door affording access to said drum through an opening common to said casing parts, said door being hinged to one of said parts and 20 fastened to the other part when closed, and provided with a rigid finger arranged to contact with said drum when the door is closed, substantially as hereinbefore specified. 25
